BOTTLE OR SIMILAR ARTICLE

Livingston C. Douglas, Leonia, N.J., assignor to Colgate-Palmolive Company, New York, N.Y., a corporation of Delaware

Filed Nov. 5, 1963, Ser. No. 77,291

Term of patent 14 years

(Cl. D58—9)

FIG. 1 is a side elevational view of a bottle or similar article embodying my new design;

FIG. 2 is a top plan view thereof;

FIG. 3 is a bottom view thereof;

FIG. 4 is a front view thereof; and

FIG. 5 is a rear view thereof.

The characteristic features of my design reside in the closed cargo carrying portion in combination with the truck cabin and body frame posterior to the truck cabin wherein the closed cargo carrying portion has a substantially oval cross-section with the height approximately equal to the height of the uppermost portion of the truck cabin and one end of the closed cargo carrying portion is attached to the truck cabin by a buffer zone, as shown.

I claim:

The ornamental design for a bottle or similar article, as shown and described.
